UNITED STATES PATENT OFFICE

109,104

DESIGN FOR A DRESS

David William Price, New York, N. Y.

Application February 7, 1938, Serial No. 74,947

Term of patent 3½ years

To all whom it may concern:

Be it known that I, David William Price, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

The characteristic feature of my design resides in the combination on the dress disclosed, of the particular blouse section which is embroidered in the manner shown, in combination with the detachable skirt of contrasting color.

I claim:

The ornamental design for a dress, substantially as shown, and described.

DAVID WILLIAM PRICE.
